CLEANING FLUID FOR DESLUDGING
INTERNAL-COMBUSTION ENGINESWilliam J. Ebel, White Plains, N. Y., assignor to
Neil McEwen, Sr., Franklin Square, N. Y.No Drawing. Application June 26, 1947,
Serial No. 757,323

4 Claims. (Cl. 252—127)

1

This invention relates to improvements in the art of desludging internal combustion engines, including not only an improved desludging mixture, but also an improved process for producing a desludging mixture, and an improved method of using a desludging mixture in internal combustion engines and the like.

Among the objects of the present invention, it is aimed to provide an improved method of desludging the crankcase and associated parts of an engine, such as an internal combustion engine, Diesel engine and the like, which will merely require removing the crankcase oil and introducing instead thereof an improved desludging mixture which will not only effectively desludge the interior of the crankcase and associated parts, but have a lubricating effect on the operative parts so that upon operation of the engine for a predetermined period of time there will result not only an effective desludging action, but also simultaneously an effective lubricating action on any operative parts brought into contact with the desludging mixture to protect the same from scuffing, scarring, or injury of any kind.

More specifically, the present invention also aims to provide an improved desludging mixture characterized by a high lubricating value and film strength and also by a high solvency on sludge and other deposits formed in the crankcase and on associated parts of an engine as a result of use, which mixture can replace the crankcase oil, and then while the engine is operating, not only serve to lubricate the operating parts, but also effectively to desludge the interior.

Still furthermore, the present invention also aims to provide an improved process for making a desludging mixture which will serve as a lubricant while the engine is operating and at the same time effectively desludge the interior.

The term sludge as herein used includes two general types, such as cold engine sludge and the hot engine sludge. The sludge in an engine is usually a mixture of both types in various proportions. This sludge is usually a mixture of water such as products of combustion, dirt such as earthy material, unburnt fuel, and oil, thickened with oxidation and thermal decomposition products plus metallic particles worn and scuffed from the sliding surfaces in the cylinders and bearing areas. Although the formation and deposit of sludge in the crankcase and on the associated operative parts of an internal combustion engine, Diesel engine and the like are well known, it may be well to point out that such sludge and deposits not only interfere with the operation of operating

2

parts, the freezing or sticking of piston rings, pistons and valves, but may also coat or block the oil pump screens and thereby prevent the flow of oil to the bearings and operative parts with the consequent injury to the same, or else actually break or fracture the oil pump screen and permit the passage of objectionable matter to the bearings and operative parts with resulting injury.

This sludge takes the form of a pasty or semi-solid material with a consistency resembling soft mud, composed of a liquid mixed with other materials, some soluble and others insoluble, in the liquid, all thickening the liquid to various consistencies. The extremes in variation run from a soft ooze to a transparent lacquer glazing the piston skirt.

The oxidation products of the oil and the fuel vary over a wide range and include soft and hard oil-insoluble resins. Some of these resins are so dark, hard, and oil-insoluble that they resemble carbon or coke.

The oxidation products may also include water resulting from the burning of the fuel or oil, or both in the combustion chamber and lead salts resulting from the burning of tetraethyl lead when a leaded fuel was used.

The principal difference between hot engine sludge and cold engine sludge resides in the fact that hot engine sludge contains large amounts of resins resulting from the oxidation of the oil in the crankcase, but is relatively free from water and soot, while cold engine sludge is relatively free from resins resulting from the oxidation of the oil. Both types, however, contain leaded salts if leaded fuel was used.

Oil which contains dissolved oxygen or is exposed to oxygen in storage gradually forms sludge. Furthermore, the sludges are not the same for different oils or for the same oil which has been subjected to different types and different degrees of refinement.

Still furthermore, there are sludges which are distinctly acid sludges, which are formed by the oxidation, condensation and polymerization of the more reactive hydrocarbons present in the refined oil. These sludges are viscous and brownish in color. On the other hand, there are sludges which consist of iron or copper salts of organic acids, the latter formed in service through oxidation of the oil and subsequent reaction with metals. There are also non-acidic constituents of sludges which are at present classified in an arbitrary manner similar to that employed for asphalts, that is, on the basis of the solubility characteristics of various solvents.

The constituents of the sludge which are soluble in petroleum ether and not adsorbed from such solutions by fuller's earth or other activated clays are classified as oils. The constituents of the sludge soluble in petroleum ether but removed from solution by adsorbents are classified as resins.

The constituents insoluble in petroleum ether but soluble in benzene are termed asphaltenes. The constituents insoluble in benzene but soluble in carbon disulfide are known as carbenes. The constituents insoluble in all of these solvents are known as carboids.

The term petroleum ether as here used includes the lightest liquid fractions distilled from petroleum, of an end boiling point not above 175° F. The term benzene as here used refers to the aromatic hydrocarbon C_6H_6 , and does not mean gasoline.

The preceding description covers in general the sludges produced in the lower section of the crankcase, namely on the oil-screen, in the sump and adhering layers on the rods, wall and pan. In addition to the foregoing, there are also encountered deposits formed on the piston skirt and ring groove area. A study of deposits removed from stuck piston rings showed them to be of a highly acidic nature. Extractions by a solution of four parts benzene and one part alcohol indicated on titration these deposits contain acids of a relatively high acid strength. No specific identification has been made of these acids except as Acids I, II, III, and so on, differing from each other on the basis of the different solvents capable of holding them in solution. From the studies made in piston ring deposits, there is a basis for assuming that the lubricating oils oxidized to produce among other products, oxyacids, which because of a tendency to condense chemically into insoluble deposits, constitute the source or cause of ring sticking.

In view of this heterogeneous nature of the sludges and deposits formed in an internal combustion engine and the like, the removing of the same has heretofore constituted a stubborn problem. As an instance, several methods have been employed to solve this problem, all accompanied with fatal objections from a practical standpoint.

One method contemplated disassembling all of the engine parts and dipping them into a vat containing the particular cleaning liquid then produced. The cost of this method not only necessitated by the disassembling of the engine, cleaning operation and reassembling of the engine, but also by the loss of use of the vehicle while so being treated made this method extremely costly and impractical.

Another method contemplated adding a small percentage of the cleaner selected as an additive to the usual engine lubricating oil when the cleaning period extended from at least a month to an indefinite period, depending to a certain extent upon the use of the vehicle. The indefiniteness of the time required for this cleaning operation made this method absolutely unreliable from a practical standpoint.

A third method contemplated replacing the lubricating oil with a flushing agent. It was recognized that such flushing agent would have to possess a lubricating value in order to protect the operating parts of the engine while operating with the flushing agent. All of the attempts with this third method at solving the problem,

however, seemed to have been blinded by the viewpoint that they required a hydrocarbon lubricating oil to impart a lubricating value to the flushing agent, and then only by the addition of a large amount of such lubricating oil frequently equaling up to ninety per cent by volume of the flushing agent. However, lubricating oil substantially decreased the solvency properties of the cleaning fluid used and therefore materially impaired, if it did not entirely destroy, the cleaning efficacy of the cleaning fluid.

With the foregoing in mind, the present invention aimed in the first place to produce an improved method of desludging engines by displacing the lubricating oil with the cleaning fluid without disassembling the engine, and operating the engine for a comparatively short period of time, the cleaning fluid of which possessed a lubricating value imparted thereto not mainly, if at all, by a lubricating oil, but by a green soap or the like which did not impair the cleaning efficacy of the cleaning fluid, and if anything, only weakened the same insignificantly.

With the foregoing in mind, it was still another object of the present invention to produce an improved cleaning mixture which had a range of boiling points so that during the cleaning operation the stripping of the lighter volatile constituents within the crankcase at a cleaning temperature of approximately 140° F. would result in effecting a cleaning action to otherwise inaccessible crankcase parts, such as the valve compartments of an L-head engine. Furthermore, it was an object to produce a composition possessing a mild alkalinity of the order of pH 9 that is in no way corrosive to alloyed bearings or aluminum parts but definitely effective on acid sludges. Still furthermore, in order to dissolve the gummy binder that causes piston ring sticking, it was an object of the invention to permit the use of a cleaning fluid in quantities approximately doubling the quantity of the crankcase oil ordinarily required so that the flushing cleaner could pass up through the oil holes behind the oil control rings and reach the ring zone area, in turn to facilitate the cleaning fluid to splash up into the interior of the piston and by virtue of its light viscosity approximating thirty-five to forty seconds at 100° F. to penetrate the clearance space between the cylinder walls and the piston skirt.

In the practice of this invention, excellent results have been achieved when the final cleaning fluid, depending upon the use intended, consisted essentially in the following:

Example I, when intended for use on heavy duty Diesel engines could consist to advantage of

60 17.0 parts by weight of soap
22.5 parts by weight of alcohol
30.5 parts by weight of ethylene dichloride
30.0 parts by weight of cresol.

65 Example II, when intended for use on heavy duty gasoline engines and heavy duty Diesel engines could consist of

18.0 parts by weight of soap
24.0 parts by weight of alcohol
32.0 parts by weight of ethylene dichloride
26.0 parts by weight of cresol.

Example III, intended for use on the engines of passenger cars and small package cars of a capacity of three-fourths to one and one-half tons,

where the motor has been used for more than thirty thousand miles, could consist of

15.6 parts by weight of soap
20.3 parts by weight of alcohol
27.9 parts by weight of ethylene dichloride
26.8 parts by weight of cresol
10.4 parts by weight of naphtha.

Example IV, when intended for use on the engines of passenger cars and small package cars of a capacity of three-fourths to one and one-half tons, where the motor has been used up to but not exceeding thirty thousand miles, could consist of

16.0 parts by weight of soap
21.0 parts by weight of alcohol
28.0 parts by weight of ethylene dichloride
24.0 parts by weight of cresol
11.0 parts by weight of naphtha.

In the aforesaid examples, the soap is preferably of the type known as green soap consisting essentially of linseed oil, soy bean oil, and the like vegetable oil, saponified by potash with no additional detergents, the soap being preferably of a plastic of semi-solid consistency.

The alcohol selected is preferably isopropyl alcohol; the cresol selected is preferably of the type characterized as 2° metaparacresol containing approximately fifty-nine per cent metacresol; and the naphtha employed is preferably of the high flash type having a distillation range from 300° F. up to 400° F.

In the aforesaid examples, the soap is added to provide the necessary film strength to prevent scuffing and seizing of the rubbing parts. One possible additional purpose is to maintain the proper alkalinity expressed as a pH value of 9. The isopropyl alcohol acts primarily as a vehicle to hold the soap and as a solvent for the alcohol soluble resins of the sludge. Certain of the oxy-acids identified in the lacquers that coat the piston skirt ring zone areas also dissolve in the alcohol. The ethylene dichloride, on the other hand, serves as a solvent for other resins in the piston lacquer and sludge that are insoluble in the alcohol. Under present conditions of analyses, the oxyacids in the piston lacquer have been identified as Acids I, II and III, soluble in different solvents. Acid I, soluble in alcohol by extraction releases a residue that upon saponification with potash and filtration can be extracted with ether or ethylene dichloride to dissolve Acids II and III. The cresol, on the other hand, is a powerful solvent for those insoluble tarry deposits that are not soluble in the aforesaid solvents. Cresol, in turn, present in coal tar, can become a tar solvent. Extensive experimentation has conclusively proved that diminishing the proportions of cresol from those specified in the several examples results in the partially cleansed engine crankcase interiors, especially when the sludge is of the hard baked type of long duration on the oil screen and in the ring zone.

The naphtha serves primarily as an extender and as a solvent for desludging resins occurring in the crankcase sludge on the piston.

The solvency of the various ingredients aforesaid necessarily overlap to some extent, but the absence of any one of the ingredients becomes immediately noticeable both in the thoroughness and speed of the desludging process.

The naphtha is also used to decrease the cost, serving to a certain extent to replace some of the other more expensive ingredients. On the other

hand, when the mixture is to be transported great distances, in the interest of package economy, the naphtha is preferably eliminated. In other words, the transportation cost in such instances would more than make up the difference in cost between the naphtha and the more expensive ingredients.

In general, the cleaning fluid consists essentially of a mixture of about 15 to 18 parts by weight of green soap of a semi-solid consistency composed of a potash saponified vegetable oil of the group consisting of linseed oil and soy bean oil, about 20 to 24 parts by weight of isopropyl alcohol, about 27 to 32 parts by weight of ethylene dichloride, and about 24 to 30 parts by weight of cresol. In turn, for some purposes there may be added to the mixture about 10 to 11 parts by weight of a high flash naphtha having a distillation range from 300° F. up to 400° F.

The process of making this mixture also presents certain advantages and is considered novel and important. The process consists essentially in dissolving about 15 to 18 parts by weight of the green soap of a semi-solid consistency composed of a potash saponified vegetable oil in about 20 to 24 parts by weight of the isopropyl alcohol when heating the same to a temperature of 110° F. and allowing the same to continue for about 45 minutes, until the temperature reaches approximately 140° F. Throughout this heat treatment, the mixture is agitated. After reaching the temperature of about 140° F., about 27 to 32 parts by weight of the ethylene dichloride is added which will immediately lower the temperature to about 120° F., and materially reduce vaporization losses. After the ethylene dichloride has been effectively stirred into the mixture, then about 24 to 30 parts by weight of the cresol and about 10 to 11 parts by weight of the naphtha are added in the order named while maintaining agitation. The complete mixing process for a quantity of one thousand pounds should not exceed one and one-half hours.

Obviously the aforesaid mixture will omit the addition of the naphtha when it is to be eliminated to produce Examples I and II, aforesaid.

The method of using the aforesaid mixture in desludging an engine is also believed to be new and important. Excellent results have been achieved when a mixture, such as outlined in Examples I to IV, inclusive, were selected as the cleansing liquid and introduced into the crankcase of the internal combustion engine after draining the used lubricating oil. The quantity of cleaning liquid, however, was approximately twice as much as the lubricating oil ordinarily used. Thereupon the motor was initially run for at least one hour with the idling speeds set to anything below 1000 R. P. M., but preferably not lower than 750 R. P. M. With a six cylinder valve in head 90 H. P. engine, theretofore used in hard fast driving, after an hour's run as aforesaid set for an idling speed of 750 R. P. M., it was found that the engine had increased in idling speed to approximately 1200 R. P. M. In place of this method, after the mixture has been introduced into the crank case, excellent results have also been achieved when the motor was initially run for only ten minutes at an idling speed between 750 and 1000 R. P. M., the ignition then shut off and the motor and cleaner allowed to stand for one hour, and then the motor again operated for a period of about one hour set at a speed of between 750 and 1000 R. P. M.

It has also been found that the soap can be reduced in quantity with a small amount of lubricating oil to supplement the lubricating function of the soap, but that when the lubricating oil exceeded ten per cent by weight of the entire mixture, the cleaning efficiency was materially affected.

It is obvious that various changes and modifications may be made to the steps in the method of operation, to the steps in the process of making the mixture, and to the percentages of the ingredients without departing from the spirit of the invention as set forth in the appended claims.

I claim:

1. A cleaning fluid for desludging internal combustion engines while operating, consisting essentially of a mixture of about 15 to 18 parts by weight of green soap of a semi-solid consistency composed of a potash saponified vegetable oil of the group consisting of linseed oil and soy bean oil, about 20 to 24 parts by weight of isopropyl alcohol, about 27 to 32 parts by weight of ethylene dichloride, and about 24 to 30 parts by weight of cresol.

2. A cleaning fluid consisting essentially of the mixture set forth in claim 1 and of about 10 to 11 parts by weight of a high flash naphtha having a distillation range from 300° F. to 400° F.

3. The process of making a cleaning fluid for desludging internal combustion engines while operating, consisting essentially in mixing and agitating about 15 to 18 parts by weight of green soap of a semi-solid consistency composed of

5 a potash saponified vegetable oil of the group consisting of linseed oil and soy bean oil, with about 20 to 24 parts by weight of isopropyl alcohol, heating the mixture to a temperature of about 110° F., and thereupon increasing the temperature to about 140° F., thereupon adding about 27 to 32 parts by weight of ethylene dichloride and reducing the temperature to about 120° F., and thereupon adding about 24 to 30 parts by weight of cresol while continuing the agitation.

10 4. The process as set forth in claim 3 characterized by adding simultaneously with the cresol about 10 to 11 parts by weight of a high flash naphtha having a distillation range from 300° F. to 400° F. while continuing the agitation.
